UNITED STATES PATENT OFFICE.

JOSEPH J. HART, OF NEWARK, NEW JERSEY, ASSIGNOR TO THE CLARK THREAD COMPANY, OF NEWARK, NEW JERSEY, A CORPORATION OF NEW JERSEY.

BUNDLING MACHINE.

Application filed September 23, 1926. Serial No. 137,202.

The invention relates to an improvement in machines for collecting and bundling articles by wrapping and fixing a band around a predetermined number of the collected articles, and is more particularly an improvement in the machine of the patent to M. O. Clauss, 1,401,520, dated December 27, 1921. The object of the invention is to secure a more efficient operation of the mechanism disclosed in said patent. To this end the invention consists in the mechanism hereinafter described and particularly pointed out in the appended claims.

In the accompanying drawings illustrating the preferred form of the invention Fig. 1 is a rear elevation of so much of the machine shown and described in said patent as is necessary to illustrate the application of the mechanism of the present invention thereto; Fig. 2 is a side elevation partly in section, of the parts shown in Fig. 1; Fig. 3 is an enlarged side elevation showing more particularly the parts constituting the mechanism of the present invention; and Fig. 4 is a detail illustrating the mode of operation of the hook device for arresting the bundle carrier for a predetermined period during its rotation.

As described in said patent, the predetermined number of articles to be gathered together in a compact bundle are received in the first instance in a gathering device indicated generally by the receptacle 10 mounted on the upper ends of the bars 11 fastened at their lower ends on the shaft 12 journaled in the front of the frame 13 of the bundling machine. When the pocket 14 of the receptacle 10 has been filled with articles by the feeding mechanism, generally indicated at 15, the active part 16 of the cam plate 17 mounted on the shaft 18 engages a roll 20 carried by one arm of a bell crank lever 22 the other arm of which is pivotally connected with the upper end of a link 24 the lower end of which is connected with an arm 25 extending rearwardly from the shaft 12. This action causes the shaft 12 to be oscillated slightly to swing the pocket 26 into alignment with the feeding mechanism 15. When the pocket 26 of the receptacle 10 has been filled with articles and the gathered articles are then in condition to be bound into a compact bundle, the pin 27 projecting rearwardly from the cam plate 17 engages with the roll 28 carried by one arm of a

bell crank the other arm 29 of which is pivotally connected with the upper end of a link 30 the lower end of which is connected with a hub 31 mounted on a stud 32 fixed in the machine frame. The oscillation of the hub 31 causes the arm 33 to release a dog 34 carried by a disk 35 mounted on a shaft 37 and thereby permit the spring 38 to force the hooked end 39 of the dog 34 into the path of rotation of the pins 41 projecting laterally from a plate 42 mounted on a sleeve 43 which carries a worm gear 44 driven by a worm 45 mounted on a shaft 46 which receives its actuation from a pulley 48. The actuation of the shaft 37 by its connection with the sleeve 43 causes the cam part 49 of the disk 35 to engage with the roller 51 mounted on the end of the arm 52 extending rearwardly from the shaft 12 and thereby cause the receptacle 10 to be swung rearwardly to insert the gathered articles into the open jaws 53 of a bundle carrier 54 mounted on a shaft 55 journaled in the blocks 56 on the rear of the frame of the machine.

Before the receptacle 10 is swung rearwardly to deposit the gathered articles into the bundle carrier 54 a paper feed mechanism, generally indicated at 57, is operated to draw a length of paper or other wrapping material from the roll 58 and position it in front of the open jaws 53 of the bundle carrier 54, so that as the receptacle 10 deposits the gathered articles in the open jaws of the carrier it carries the strip of paper in with them. The adhesive applying wheel 59 is then actuated from the cam 62 mounted on the shaft 37 to apply glue to the lower flap of the wrapper and fold it upwardly onto the articles. The shaft 55 is then rotated to swing the carrier 54 in the direction indicated by the arrow in Fig. 2, thereby causing the upper flap of the wrapper to be folded down over the lower adhesive coated flap. The travel of the carrier 54 in the direction indicated removes the gathered articles out of the open upper end of the receptacle 10, all as fully described in said patent. The means for rotating the shaft 55 comprises a disk 60 mounted on a sleeve 61 journaled on the shaft 55. The sleeve 61 is constantly driven from the sleeve 43 by the chain 63. On the shaft 55 is mounted an arm 64 which carries a dog 65, the hooked end 66 of which is normally held out of the path of rotation

- of the pins 67 projecting laterally from the disk 60 by means of an arm 68 which engages a pin 69 carried by the dog 65. The arm 68 is mounted on the front side of a hub 70 journaled on the stud 32. On its rear side the hub 70 carries an arm 71 on the outer end of which is mounted a roller 72 adapted to be engaged by a pin 73 fixed in the outer end of an arm 74 mounted on the shaft 37.
- 10 When the shaft 37 is caused to rotate by the engagement of the pin 27 with the roller 28 the pin 73 encounters the roller 72 and thereby oscillates the hub 70 to disengage the arm 68 from the pin 69. Thereupon the spring 15 76 moves the hook-like end 66 of the dog 65 into the path of rotation of the pins 67 to drive the shaft 55 from the sleeve 61. As shown and described in said patent the bundle carrier 54 makes a complete revolution 20 and returns to its initial article-receiving position when the engagement of the arm with the pin 69 again disengages the shaft 55 from driving connection with the sleeve 61.
- 25 During the rotation of the bundle carrier 54 the roller 80 carried by the movable jaw 81 of the carrier encounters a cam 82 formed on the end of a sleeve 83 secured in adjustable position by the clamp 84 to one of the 30 blocks 56, and thereupon the jaw 81 is opened and the bundle of articles permitted to fall out of the carrier 54 into a receptacle provided for them.
- It has been found that the discharge of the 35 bundle of articles during the continuous rotation of the carrier 54 does not permit the adhesive on the wrapper to set, so that the wrapper frequently opens and the bundle of articles falls apart, necessitating regathering.
- 40 According to the present invention the bundle carrier 54 is arrested during its rotation and held stationary long enough to permit the adhesive to set, so that when the carrier is again put in motion and the jaw 81 actuated to release a bundle, the wrapper will remain about the bundle of articles, holding them firmly together. For this purpose I provide a lever 85 pivotally mounted on the pin 93 in the lower end of a plate 86 45 extending downwardly from the cross-piece 87 supported on the upper ends of the rods 88 rising from the journal blocks 56. The lever 85 is provided with a curved arm 89 the lower hook-like end 90 of which is normally pressed into the path of rotation of the pin 69 of the dog 65 (when the latter has been released by the arm 68) by means 50 of a coiled spring 91 one end of which is fastened to the arm 89 and the other end of which is fixed in a collar 92 adjustably secured on the pivot pin 93. The engagement of the pin 69 by the hooked end 90 of the arm 89 disengages the dog 65 from one of the pins 67 of the plate 60, thereby disconnecting 55 the sleeve 61 from driving connection

with the shaft 55 and causing the bundle carrier 54 to stop before it has passed out of engagement with the arcuate guide 95 which serves to hold the outer flap of the wrapper against the adhesive covered under flap. The 70 bundle carrier 54 is held arrested sufficiently long to permit the adhesive to set so that when the bundle of articles is discharged from the carrier the wrapper will hold the articles in a compact bundle. 75

The means for disengaging the arm 89 from the pin 69 of the dog 65 to permit the dog to reestablish its connection with one of the pins 67 of the plate 60 comprises an arcuate boss 96 fixed on the rear surface of the 80 cam disk 17 and near the periphery thereof. The boss 96 is adapted to move into engagement with the upper end of a rod 97 pivotally connected at its lower end with the arm 98 of the lever 85 and mounted at its 85 upper end for vertical movement on the bracket 99 which serves to support the outer end of the shaft 18 on which the cam disk 17 is mounted. The upper end of the rod 97 is slotted vertically at 101 to receive a 90 screw 102 fixed in the bracket 99. When the boss 96 encounters the upper offset end 103 of the rod 97 it depresses the rod, thereby causing the lever 85 to be oscillated in a counter-clockwise direction, viewing Figs. 95 3 and 4, so as to disengage the hooked end 90 of the arm 87 from the pin 69, as shown in dotted lines in Fig. 4. Thereupon the dog 65 resumes its connection with one of the pins 67 of the plate 60, reconnecting the 100 sleeve 61 with the shaft 55 and causing the bundle carrier to complete the remainder of its rotation, during which the securely wrapped bundle is discharged. As described in said patent, the rearward swing of the 105 article receptacle 10 into discharging position takes place when the cam surface 104 on the cam plate 17 encounters the roller 20. The plate 17 travels in the direction of the arrow indicated on Fig. 1. The bundle carrier 54 begins its rotation immediately after the gathered articles have been deposited into the open jaws of the carrier by the receptacle 10. It will be seen therefore that the 110 length of time the carrier 54 is held arrested will depend upon the position of the hooked arm 89 and the position of the boss 96 on the plate 17. When the rotation of the plate 17 carries the boss 96 beyond the end 103 of the rod 97 the hooked end 90 of the arm 87 returns to normal position under the action of the spring 91. 115

Having thus described the invention what I claim as new is:—

1. A machine of the character described having, in combination, means for gathering together the articles to be made into a bundle, a carrier for receiving the gathered articles, means for wrapping a binder around the articles, means for applying adhesive to the 125 articles, means for

binder, a shaft on which the carrier is mounted, a constantly driven sleeve journaled on the shaft, means for operatively connecting the sleeve and the shaft to cause the latter to make a complete rotation, and means for temporarily disconnecting the sleeve from the shaft during the rotation of the latter to permit the adhesive to set.

5 2. A machine of the character described having, in combination, means for gathering together the articles to be made into a bundle, a carrier for receiving the gathered articles, means for wrapping a binder around the articles, means for applying adhesive to the binder, a shaft on which the carrier is fixed, a constantly rotating member, means for operatively connecting the member with the shaft to cause the latter to make a complete rotation, and means for disconnecting 10 the member from the shaft during the rotation of the latter to cause the shaft to be temporarily arrested to permit the adhesive to set.

15 3. A machine of the character described having, in combination, means for gathering together the articles to be made into a bundle, a carrier for receiving the gathered articles, means for wrapping a binder around the articles, means for applying adhesive to the binder, a shaft on which the carrier is fixed, a constantly driven sleeve journaled on the shaft, a disk fixed on the sleeve, pins 20 projecting laterally from the disk, a dog

25 mounted on the shaft adapted to engage with the pins on the disk whereby the shaft is driven through a complete rotation by the sleeve, a pin on the dog, an arm normally held in the path of rotation of the pin on the dog to disconnect the dog from the pin on the disk to cause the shaft to be arrested in its rotation, and means for disconnecting 30 the arm from the pin on the dog to permit the shaft to complete its rotation.

4. A machine of the character described having, in combination, means for gathering together the articles to be made into a bundle, a carrier for receiving the gathered articles, means for wrapping a binder around the articles, means for applying adhesive to the binder, a shaft on which the carrier is fixed, 45 a constantly rotating disk, pins projecting laterally from the disk, a dog mounted on the shaft adapted to engage with one of the pins of the disk whereby the shaft is driven through a complete rotation by the disk, a pin carried by the dog, a lever arm having 50 a hooked end normally held in the path of rotation of the pin on the dog to disengage the dog from the pin on the disk to arrest the rotation of the shaft, and a cam arranged to actuate the lever arm to disengage its hooked end from the pin on the dog to permit the latter to reengage one of the pins on the disk to cause the shaft to complete its rotation.

JOSEPH J. HART.
